UNITED STATES PATENT OFFICE.

ROBERT FREDERICK HALL, OF BIRMINGHAM, ENGLAND.

CHAIN-GEAR CASE FOR CYCLES.

SPECIFICATION forming part of Letters Patent No. 553,461, dated January 21, 1896.

Application filed September 5, 1895. Serial No. 561,554. (No model.) Patented in England May 7, 1895, No. 9,001.

To all whom it may concern:

Be it known that I, ROBERT FREDERICK HALL, managing director of the Cycle Components Manufacturing Company, Limited, 5 and a subject of the Queen of Great Britain, residing at Ferndale, Church Road, Moseley, in the city of Birmingham, England, have invented a certain new and useful Chain-Gear Case for Cycles; and I do hereby declare the following to be a full, clear, and exact description of the invention, reference being had to the accompanying drawings, which form part of this specification, and for which said invention I have obtained Letters Patent 15 of Great Britain, dated the 7th day of May, 1895, and numbered 9,001.

This invention has relation to detachable and oil-containing gear-cases for cycles, and has for one of its objects a simple means of 20 attachedly connecting the said gear-case to that stay of the back-forks coming on the chain-wheel side of the machine; for another object the making of the joints of the case oil-tight, and for a further object so 25 building or making the foundation-framing to which the divided sections of the casing are attachedly connected that when fitted the same are perfectly rigid and noiseless.

Figure 1 of the accompanying drawings 30 represents a front elevation of a fitted detachable and segmental chain-gear case constructed, arranged, and provided with improvements made according to my invention. Fig. 2 represents a back elevation of the same. Fig. 3 represents the principal component parts of the said gear-case separated, showing the organization of the foundation-strip, which is itself made sectional with the sections united at the middle. Fig. 4 represents an edge view of the bottom part of the case, with the foundation-strip in elevation. Fig. 5 represents a vertical cross-section of the case upon the dotted line x , Fig. 1. Fig. 6 is a vertical cross-section of Fig. 1 upon the 40 dotted line x' . Fig. 7 represents a like cross-section as Fig. 6, but with the halves of the case separated and removed from the foundation-strip. This case or cover, which forms an oil-bath for the chain and chain-wheel to 45 run within, is separated from the foundation-strip secured to the chain-wheel-side member of the back forks. Fig. 8 represents a cross-

section of the case upon the dotted line x^2 , Fig. 1, showing how the supporting-stay of the case comes exteriorly of the casing, instead of interiorly, as heretofore. Fig. 9 represents a section upon the dotted line x^3 , Fig. 1, while Fig. 10 is a cross-section of Fig. 1 upon the dotted line x^4 , Fig. 1, which view is alike unto Fig. 8, but shows the stay running out through the left-hand side of the case. Fig. 11 is an enlarged sectional view of a grooved edging part of the casing. Fig. 12 is a top side plan of the foundation-strip in position upon the carrying-stay, and Fig. 13 65 is a longitudinal section of the same. Fig. 14 represents the component parts of the foundation-strip separated from each other and from the stay. Fig. 15 is a section of the rear portion of the strip upon the dotted line x^5 , Fig. 14, and Fig. 16 is a like section of the forward part of the strip upon the dotted line x^6 , Fig. 14, showing the set-back troughed character of the strip.

The same letters of reference indicate corresponding parts in the several figures of the drawings.

The gear-case is made of two fitted together horizontal sections or halves a a' with the opposed or meeting edges a^2 of the forward part 80 of the front of one section, which is tongued, taking into the presented grooved edges a^3 of the forward front part of the other section, and with the like tongued edges a^4 of the after part of the back of one section engaging with 85 the opposed grooved edge a^5 of the after part of the back of the other section, the inner parts a^6 of the grooves at both back and front extending higher than the front edges of the said grooves, which are each made from a single strip of metal folded upon itself, as best 90 seen in Fig. 11. The front sides of the after parts of the sections of the said two-part case have clearances a^7 , which, when the sections are brought together, form a longitudinal gap 95 a^8 , extending throughout about one-half of the entire length of the case, with the top and bottom edges a^9 a^{10} being grooved, into which the opposite tongue-flanges b' of the after part b^2 of a foundation strip b , whose fore 100 part is marked b^3 , take, so as to make an oil-tight joint between the said parts. The back sides of the front parts of the said sections also have like clearances a^{11} , which form a

longitudinal gap a^{12} , extending through a larger part of the middle of the said front of the casing, and having the top and bottom grooved edges $a^{13} a^{14}$, to take upon the tongue-
5 flanges b^4 of the said fore part b^3 of the foundation-strip b . The bottom bracket chain-wheel end of the foundation-strip has a hat-shaped boss b^5 with the circular flange b^6 , onto which the grooves $a^{15} a^{16}$ of corresponding
10 semicircular gaps a^{17} , formed in each half of the sections, take, while the extreme front ends of both sides and also the front side of the rear end of the said sections are furnished with groove-and-tenon joints $a^{18} a^{19}$.
15 The foundation-strip b is built up of longitudinal halves $b' b^8$, each having troughed or set-back channels $b^7 b^8$, presented in opposite directions and running in the same axial lines and with their opposed ends fitted with
20 stepped junctions $b^9 b^{10}$ interlocking with one another, and each being semicircularly and coincidentally gapped they form a complete circular opening b^{11} , wherethrough the oblique stay c' on the chain-wheel side of the back
25 forks c passes when lying within the channels, but outside the casing.

The sections of the junction-piece of the foundation-strip are united together by small screws b^{12} , while the middles of the sections
30 of the casing are secured to the foundation-strip, through the medium of the said junction, by small screws d , passing through the sides of the casing and into the solid metal of the junction. The case at its bottom bracket
35 end is further secured to the stay by an adjustable band-clip e , attached to the back of the forward half of the foundation-strip and drawn around the stay c' by a screw-pin e' . The fore part of the stay terminates in a bottom bracket e^3 , having front and seat-rod framing members $e^4 e^5$, directed from it and carrying a pedal-axle e^6 , carrying a chain-wheel e^7 for driving a chain f , communicating motion to the chain rear wheel g , secured on
40 the hub g' of the back wheel. The back of the case, adjacent to the said hub, is fitted with

sectional and adjustable slides $h' h^2$, working within grooves $a^{20} a^{21}$ of the halves of the case.
i are chain-adjustment fork ends of the stays c' , and j are the back stays.

Having fully described my invention, what I desire to claim and secure by Letters Patent is—

1. In chain-gear cases for cycles, the combination with sectional halves of the case, of 55 a two-part foundation strip, with the sections inversely troughed and disposed in the same axial line and with their opposed ends united together by semi-circularly gapped junction ends, substantially as and for the purpose described and set forth.

2. In chain-gear cases for cycles, the combination with sectional halves of the case, 60 united together by groove and tongue joints, of a two-part foundation strip, whose sections 65 are inversely troughed and disposed in the same axial line and have their opposed ends united together by semi-circularly gapped and stepped junction pieces secured to one another, and the sections of the case to them, 70 by screws, substantially as described and set forth.

3. In chain-gear cases for cycles, the combination with the sectional halves of the case 75 and with a framing stay, of a foundation strip built up of longitudinal halves each having troughed, or set-back channels presented in opposite directions and running in the same axial lines, their opposed ends fitted with stepped, interlocking junctions, each being 80 semi-circularly and coincidentally gapped to form a complete circular opening for the oblique stay on the chain-wheel side of the back forks, substantially as described.

In testimony that I claim the foregoing I 85 have hereunto set my hand this 31st day of July, 1895.

ROBERT FREDERICK HALL.
